UNITED STATES PATENT OFFICE

ERNST H. ELZEMEYER, OF ST. LOUIS, MISSOURI, ASSIGNOR TO AMERICAN PULVERIZER COMPANY, OF ST. LOUIS, MISSOURI, A CORPORATION OF MISSOURI

PULVERIZING MACHINE

Application filed October 9, 1925. Serial No. 61,562.

This invention relates to pulverizing machines of the type wherein a rotor loosely supports a series of annularly spaced rings adapted to cooperate with the grinding surfaces of the pulverizing machine.

The principal object of the present invention is an improved ring for pulverizers of the above type that will overcome the tendency for the material to pack on the grinding surface of the pulverizer under the rolling action of said ring, and thereby increase the efficiency of such machine. Other objects are simplicity and cheapness of construction and compactness of design.

15 The invention consists principally in a pulverizing ring whose peripheral surface is formed with reversely curved or undulating side edges; and it also consists in the parts and in the arrangements and combinations of parts hereinafter described and claimed.

20 In the accompanying drawing, which forms part of this specification, and wherein like symbols refer to like parts wherever they 25 occur,

Fig. 1 is a vertical transverse section through a pulverizing machine provided with pulverizing rings embodying my invention;

Fig. 2 is a face view of one of said rings;

30 and

Fig. 3 is an edge view thereof.

In Fig. 1 of the accompanying drawing, my invention is illustrated in connection with a pulverizer comprising a suitable casing or housing 4 provided with a hopper or chute 5 through which the material to be pulverized is fed. The main shaft 6 is mounted in bearings formed in the end walls of the casing, said end walls being provided

40 with arcuate flanges 7 which support the ends of the grinding concave 8 and the grate bars 9. Mounted on the shaft 6 in recesses provided therefor in the end walls of the casing, are end plates or disks 10. These

45 disks are keyed to the shaft 6 so as to be rigid therewith, and are connected to each other near their outer edges by a series of spaced parallel rods 11. Mounted on the shaft 6 between the disks 10 are spiders 12, the 50 radially extending arms 13 of which are per-

forated to receive the supporting rods 11 and thus form supports for the same intermediate their ends. The hub portions 14 of the spiders 12 are keyed to the shaft 6 and abut against each other, thereby spacing the arms 13 of 55 the spiders the desired distance from each other.

Loosely arranged on the supporting rods 11 between the radially extending arms 13 of adjacent spiders 12 are rings A. These rings 60 revolve with the carrier and act as percussion members to break or shatter the pieces of material and they also cooperate with the grinding surfaces and act as rollers to crush or pulverize the material over which they roll 65 or ride. Each of the rings A comprises an annular body portion having a smooth uninterrupted peripheral surface whose side edges 15 are shaped in waves or undulations; that is, each edge of the peripheral surface 70 of a ring is alternately concave and convex, the convex portion at one edge of said ring being disposed opposite the concave portion at the other edge of said ring. In order that the rings A shall have sufficient 75 weight to serve as crushing rollers, the annular body portions of said rings are made wider than their peripheral portions except at the concave portions of the rings where said portions extend inwardly from the peripheral surface of the rings to form a series of 80 annularly spaced recesses 16 in the peripheral portion of each of their side faces. These recesses terminate short of the inner periphery of the ring and their bottoms are reversely 85 curved after the manner of their sides so that said recesses are deepest at their middle and merge into the peripheral surface of the ring at their ends.

It is noted that by the arrangement described, the peripheral surfaces of the rings serve as crushing surfaces, while the undulating or reversely curved side edges thereof form cutting edges which serve as plows or scrapers for digging or loosening any material that tends to pack on the grinding surfaces of the machine and thereby impair the operation thereof. It is also noted that the reversely curved edges of the bottoms of the recesses in the side faces of the rings pro- 100

vide additional cutting edges which serve to hack or cut the material.

The foregoing arrangement is considered only as an example; therefore, I do not wish 5 to be limited to the type of machine shown, as my invention is applicable to other types of pulverizers.

What I claim is:

1. A ring for pulverizing machines comprising an annular body having a series of circumferentially spaced recesses formed in the peripheral portion of each of its side faces, the end portions of said recesses terminating in curved surfaces that are tangent 10 to the peripheral surface of said ring.
  2. A ring for pulverizing machines comprising an annular body having undulating side faces and a series of circumferentially spaced recesses formed in the peripheral portion of each of its side faces, the bottom of 20 each recess being reversely curved from the middle of said recess to the ends thereof.
  3. A ring for pulverizing machines comprising an annular body having a series of 25 circumferentially spaced recesses formed in the peripheral portion of each of its side faces, the recesses on one side of said body being disposed opposite the spaces between the recesses on the other side of said body, 30 the bottoms of said recesses being reversely curved from their middle to their ends.
  4. A ring for pulverizing machines comprising an annular body provided at the peripheral portion of each of its side faces with 35 recesses, whose sides and bottoms are reversely curved and merge into the sides and peripheral face of said body at the ends of said recesses.
  5. A ring for pulverizing machines comprising an annular body having a series of 40 circumferentially spaced recesses in its peripheral edges, said recesses being of gradually decreasing depth and width from their middle towards their ends, where they terminate in curved surfaces that are tangent to the 45 sides and peripheral surfaces of said ring.
  6. A ring for pulverizing machines comprising an annular body having a series of circumferentially spaced recesses in the marginal portions of its peripheral surface, the bottoms of said recesses extending circumferentially of said ring and the peripheries of 50 said bottoms being reversely curved from their middle to their ends.
- 55 Signed at St. Louis, Missouri, this 5th day of October, 1925.

ERNST H. ELZEMEYER.
